United States Patent Office

Des. 184,368
Patented Feb. 3, 1959

184,368

CABANA

Glenn R. Nunemaker, South Bend, Ind.

Application March 26, 1956, Serial No. 40,765

Term of patent 3½ years

(Cl. D13—1)

FIG. 1.

FIG. 2.

Figure 1 is a front perspective view of a cabana showing my new design. The rear of the building is substantially plain and the other side not shown is like the side shown; and,

I claim:

The ornamental design for a cabana, substantially as shown and described.
